DESIGN FOR A FOUNTAIN PEN OR SIMILAR ARTICLE

Walter Dorwin Teague, Annandale, N. J., and Robert J. Harper, Scarsdale, N. Y., assignors to Scripto, Inc., a corporation of Georgia

Application October 15, 1947, Serial No. 141,926

Term of patent 14 years

(Cl. D74—1)

To all whom it may concern:

Be it known that we, Walter Dorwin Teague, a citizen of the United States, residing at Annandale, county of Hunterdon, and State of New Jersey, and Robert J. Harper, a citizen of the United States, residing at Scarsdale, county of Westchester, State of New York, have invented a new, original, and ornamental Design for a Fountain Pen or Similar Article, of which the following is a specification, reference being had to the accompanying drawing, forming part thereof.

Fig. 1 is a side elevational view of a fountain pen, showing our new design;

Fig. 2 is a front elevational view corresponding to Fig. 1; and,

Fig. 3 is a top plan view corresponding to Fig. 1.

The dominant features of our design reside in the parts shown in full lines.

We claim:

The ornamental design for a fountain pen or similar article, substantially as shown and described.

WALTER DORWIN TEAGUE.
ROBERT J. HARPER.
